METHOD AND APPARATUS FOR PICTURE TRANSMISSION BY WIRE OR RADIO

Application filed October 20, 1923. Serial No. 669,638.

This invention relates to a new process and an arrangement for utilizing existing wire or wireless telegraph or telephone circuits and apparatus for the transmission of pictures and the like. We are aware that many attempts have been made in the past to provide a practical and reliable system for the transmission of pictures, more especially by wire. These systems generally are based on the transmission and simultaneous reception of electrical impulses of varying intensity corresponding to the light intensity of a sufficient number of units of the picture so that each unit can be represented by a single intensity value of the electric current. The direct result of simultaneous operation is a need for extremely accurate synchronization, such as has not been practically or economically possible in a commercial telephone or telegraph system.

The present invention contemplates a method and system in which synchronization in its ordinary sense is unnecessary, and in which coordination is accomplished without actual synchronization.

The present invention also contemplates a system in which the usual form of telegraph transmitting and receiving circuits, both wire and wireless, are utilized without change, and moreover, a system in which a mechanical transmitter, adapted to be controlled by a perforated record tape, is utilized providing for transmission of pictures at a high rate of speed.

In accordance with the broad aspect of our invention the necessity for simultaneous synchronous operation is avoided by translating the succession of light intensities into a record. The record may be made either at the transmitter or the receiver or at both. The current of a telephonic transmitter system will be modulated or the current of a telegraphic system interrupted in accordance with the succession of light intensities. This modulated or interrupted current may then be put directly on the wire or on the air, received, recorded and reproduced or it may be recorded, transmitted, received and reproduced or recorded, transmitted, received, recorded and reproduced. Usually the mod-

ulated or interrupted current will correspond to a certain succession of light intensities or a line of the picture and the record in co-ordination with the reproducing apparatus will determine the starting point of each new line or succession of impressions.

The invention may be applied to transmission of pictures with waves or currents of varying intensity similar to telephonic currents and to interrupted or telegraphic waves or currents. For convenience a particular embodiment will be described in connection with transmission by telegraphic impulses as certain features of the invention are particularly applicable thereto.

In accordance with our invention as illustrated in the particular embodiment to be described, the light intensity of areas of the picture are translated into impulses having durations corresponding to the light intensity. Preferably, all of the impulses are of the same intensity. These impulses are also preferably converted into electrical impulses and recorded on a tape before they are transmitted. Transmission may then be done whenever the telegraph circuit happens to be available and various parts of the picture may be sent at different times. At the receiving station the impulses are also preferably recorded on a tape for example. The picture is then reproduced at any convenient time by an apparatus which places an impression on the reproducing sheet which corresponds in light intensity with the duration of the impulse. Most of the apparatus used in the method may be and preferably is in the form of ordinary types of automatic recorders and perforators used in telegraphy.

This is preferably accomplished by providing means whereby the picture to be transmitted may be converted into a record tape adapted to control a mechanical transmitter to send impulses of varying duration depending upon the intensity of light in a small section of area of the picture. A receiver is provided adapted to convert received impulses into a perforated record tape in all respects similar to that produced at the transmitting end which was utilized to control the transmitter and by providing suitable reproducing

means into which the perforated tape, obtained as described, may be fed for the purpose of controlling any suitable recorder.

It is a further object of our invention to provide a system of the class described equally adaptable to wire or radio telegraphy and without disturbing in any way the usual apparatus found in such systems.

It is a further object of our invention to provide a system which shall be relatively simple in operation and comparatively economical to install.

It is a further object of our invention to provide a system of the class described utilizing an automatic mechanical transmitter and mechanical receiver, whereby pictures may be transmitted and received at a relatively high rate of speed and without the services of a skilled operator.

It is a further object of our invention to provide a system of the class described in which transmission and reproduction of the picture may take place independently and at any convenient time.

Still other objects of our invention will be apparent from the specification.

Our invention is illustrated in the accompanying drawing in which,

Fig. 1 shows diagrammatically the elements comprising the transmitting system,

Fig. 2 shows diagrammatically the elements comprising the receiving system,

Fig. 3 shows in detail a portion of the transmitter circuits and apparatus, and

Fig. 4 shows in detail a portion of the recorder circuits and apparatus.

Referring to Fig. 1, there is provided a rotatable transparent cylindrical drum 1, upon which the picture to be transmitted is adapted to be mounted. Within said drum is provided a suitable source of light 3 which may conveniently be an ordinary electric light bulb centrally disposed therein. Arranged at a convenient distance from said

drum, we provide what may be termed a "perforator controller" 5 which comprises for example a light sensitive cell and circuits controlled thereby. A lens 4 is interposed between the drum 1 and the perforator controller

5 in a manner to concentrate the light upon the sensitive cell. Suitable means for rotating the drum 1 at a proper speed is provided, such for instance as motor 2. Also, provision is made for causing longitudinal movement either of the drum 1 or of the perforator controller 5 and lens 4 in such a manner that as the drum is rotated, light from all parts of the picture to be transmitted is progressively thrown upon the light-sensitive cell.

For producing rotation of the cylinder and the relative longitudinal movement a gear 3' on the shaft of the drum meshes with a worm 2' on the shaft of the motor and with a gear 4' having a screw threaded shaft 5' for moving the lens and perforator controller longitudinally.

Suitable electrical connections are provided between the perforator controller 5 and a suitable perforator 6 adapted to perforate a tape in a manner to be described. The perforated tape is utilized to control a mechanical transmitter 7 of any suitable type and while in Fig. 1 we have shown the tape as being fed from the perforator directly into the transmitter, this is not necessary and if desired a large number of pictures may be converted into records and the records stored away until it is desired to transmit the pictures. While no transmitter circuits have been shown in this figure, it will be obvious that the transmitter 7 may control any suitable circuit, for instance a wire telegraph line in the usual way, or a wireless telegraph system, as will be readily understood by those skilled in the art.

Referring to Fig. 2, which shows diagrammatically the elements comprising the receiving system, 8 is a receiver, either wire or wireless, adapted to control some suitable apparatus for making a perforated tape record of the impulses received, such for instance as a Creed reperforator 9 well known in the art. The perforated record tape is fed to reproducer 10 which reconstructs the picture from the record tape in a manner to be described hereafter. Having indicated in a general way the general construction and operation of a system embodying the invention, the arrangement and operation will now be described in greater detail.

Fig. 3 shows the circuits of certain apparatus in the perforator controller 5 and the perforator 6, 1 being the drum and 3 the light therein. As described above, drum 1 is adapted to be rotated by means of motor 2 through suitable gearing and the light passing through the picture is concentrated by lens 4 on photo-electric cell 11. This invention is not limited to the use of a light cell and any suitable arrangement adapted to give a measure of the intensity of light may be substituted therefor.

Various arrangements may also be utilized for utilizing the variation of resistance of the cell. The arrangement herein shown has a terminal of said cell connected to suitable battery 13 which for the particular arrangement used may have an E. M. F. of about 400 volts. The positive terminal of battery 13 is connected to resistance 12 of a very high value, for instance 20 megohms. The other end of resistance 12 is connected to the other terminal of photo cell 11. For operating the system in the manner to be hereinafter described, the change in the voltage drop across the high resistance 12 is utilized. This is most conveniently accomplished through the aid of an amplifying system such as a three electrode thermionic valve amplifier consisting of one or more standard amplifying tubes connected in any well known man-

ner. For simplicity a single tube is shown although this is purely diagrammatic as sufficient amplification will be used to enable operation of the relays hereinafter referred to.

5 The grid of this tube is connected to the negative terminal of resistance 12 and the plate is connected thru series connected windings O, of relays 21, 22, 23, 24 and 25 to a suitable source for maintaining them positive, in this 10 case shown as the +110 terminal of a three wire 110 volt supply line, the neutral terminal 0 of which is connected to the filament of the tube 16.

One terminal of potentiometer 14 is connected to said neutral, the other terminal being connected through resistance 15 to the negative side -110 of the three wire supply line. The adjusting arm of potentiometer 14 is connected to the positive side of resistance 12. Potentiometer 14 may have a value of approximately 400 ohms and resistance 15 may have a value of approximately 200 ohms. Also, a suitable 6 volt source of current is provided for lighting the filament of tube 16 through the usual variable controlling resistance 18.

A commutator 19 having two segments is adapted to be traversed by a conducting arm rotated by motor 2. The rotating arm is 30 connected to the -110 side of the three wire supply line. One segment of said commutator is connected through punching coil 20 of the perforator to the neutral. The armatures of relays 21, 22, 23, 24 and 25 are 35 connected also to said neutral and the armature of relay 21 closes a circuit through perforating coil 31 to the -110 side of the three wire supply line. In the same way armature of relay 22 closes the circuit through 40 perforating coil 32 and armatures of relays 23, 24, 25 close the circuit through perforating coils 33, 34 and 35.

Each of these relays 21, 22, 23, 24 and 25 comprises two windings, an actuating winding designated as A which is arranged to attract its armature against the fixed contact and close the circuit through the perforator coil and an opposing winding O arranged to hold the said armature away from its contact leaving the perforator coil circuit open. Each of the actuating windings A of relays 21, 22, 23, 24 and 25 is connected on the one hand to the neutral of the supply source and on the other hand to the adjusting arm of 50 potentiometers 26, 27, 28, 29, 30 and connected in parallel between the positive and neutral terminals of the three wire supply, the purpose of which will be explained later.

Any suitable device may be used herein 60 for the purpose of perforating tape 36. Satisfactory results have been obtained by the use of the Kleinschmidt perforator, well-known to those skilled in the art. It may be stated that the perforating coils 31, 32, 33, 65 34 and 35 do not, by their energization in the

usual arrangements actually perforate the tape, but they control the setting of the punches corresponding thereto for operation and the paper is perforated by the action of punching coil 20.

As shown in the drawing all of the perforator coil circuits are open when there is no illumination on the picture and none of the punches are set for operation. The same would of course be the situation when the 70 light is thrown on a dark spot. When a light spot or high light is projected on the lens all the relays are closed and the punches are set for operation. However, it is not material whether the arrangement is co-ordinated to operate the punches for dark spots or high lights as reversals may be readily accomplished by reversals at any point in the transmitting or receiving apparatus. As the perforator is a well-known type it will 75 be unnecessary to illustrate anything but its essentials.

Referring now to the operation of the apparatus described, when it is desired to make a perforated record of a picture, the same 80 is placed on the drum 1 and the various circuits are closed. Drum 1 is rotated at a comparatively slow rate of speed in any suitable manner and is so arranged at the starting 85 that the light on photo cell 11 comes preferably at one corner of the picture to be transmitted. A suitable gear ratio is employed between motor 2, drum 1 and commutator 19 so that one energization of the punching 90 coil takes place for 1/32 of an inch of rotation of the drum. If closer detail is desired the distance may be made less. The light 95 from the picture falls upon photo cell 11 and the current therefrom is varied in a well-known manner; that is to say, when no light 100 falls upon the cell the resistance has a predetermined value. The greater the amount 105 of light falling upon the cell, the lower this value becomes and the greater the current flowing through the cell and also through 110 resistance 12. Inasmuch as the value of resistance 12 is high the drop in potential between the terminals of this resistance will fluctuate with the current and therefore in 115 accordance with the intensity of light in the picture to be transmitted. It will now be seen that the grid of tube 16 will receive a negative charge which will be greater in magnitude when the current through photo-cell 11 is large. That is, the lighter the 120 picture in a particular section, the greater the negative charge of the grid of tube 16 and the less the plate current. Potentiometer 14 is adjusted in a manner so that this negative charge gives a suitable effect in cutting 125 down the plate current to satisfactorily operate the relays 21, 22, 23, 24 and 25 in the manner hereinafter described.

The potentiometers 26, 27, 28, 29, 30 controlling relays 21, 22, 23, 24, and 25 and 130

potentiometer 14 are adjusted so that the perforator coils 31, 32, 33, 34, 35 are closed when the plate current is a minimum due to the projection of a high light value, that is, the actuating coils are stronger in their attraction under this condition. The strength of the actuating coils is varied progressively so that these relays will successively open in accordance with increases in the plate current of amplifier 16 corresponding to dark spots on the picture. In the arrangement shown relay 21 is adjusted to open with smaller current in opposing coil O than any of the other relays; relay 22 upon a predetermined increase in plate current and relays 23, 24 and 25 successively thereafter, if the dark spot increases the plate current sufficiently. Briefly, the light value determines the number of perforations which are made on the tape. In the arrangement connected as shown, the plate current varies inversely with the light values. The highest light values of the picture give a relatively strong negative bias on the grid of amplifier 16 through the action of resistance 12 whereby the plate current flowing through the opposing windings of relays 21 to 25 will be decreased to such a value that all of said relays will be closed by the superior attraction of the actuating coils A and coils 31 to 35 will be energized. The perforator is so arranged that by this energization all of the punches will be prepared for operation on the energization of the punching coil 20 by subsequent closure of punching coil circuit through commutator 19. It is apparent therefore that a high light in the picture causes perforation of the tape by all of the punches as shown. The circuit arrangements described are one means for determining light values and translating them into a form which may be transmitted and received as impulses of varying length. Although the arrangement shown for this purpose is a desirable one other arrangements may be used some of which will be the subject matter of separate applications. The present application will contain general claims to the novel subject matter common to the various arrangements.

Immediately upon the operation of the punching coils and the punching of the tape the same is stepped forward to a new position. It may be stated at this time that the perforations B' B' made in the lower row and B B in the upper row separate the groups of impulses which represent the light intensities of different unit areas. When put through the transmitter the perforation B comes into action prior to perforation B', due to the fact that the fingers cooperating therewith act alternately. The perforations B' of the tape cause a circuit to be closed which starts the impulse. The impulse then continues until another perforation is reached

in the upper row. In the tape punched as shown the next succeeding perforation E in the top row following B marks the termination of the said impulse and it will be seen that for a high light in a picture which causes the operation of perforating coils 31 to 35 inclusive, the impulse whose beginning is initiated by perforation B' will be almost immediately terminated by the first perforation E. Although the succeeding perforations are made by the coils 32, 33, 34 and 35 they have no effect when the apparatus is operated in the particular manner described as no impulses are again transmitted until the next perforation B' is reached when the tape is fed into the transmitter. For a value of light not quite so intense as that which causes the operation of all said relays, the relay 21 will remain open due to the fact that the negative bias upon the grids of the tubes is not quite so great and the plate current is larger whereby the coil O in relay 21 will be sufficiently energized to overcome coil A of said relay. Therefore perforating coil 31 will not be energized. However, relays 22, 23, 24 and 25 will be closed and perforator coils 32, 33, 34 and 35 will be energized. When a closure of the punching coil circuit occurs, the tape will be punched in a corresponding manner. In this case, however, an impulse of three times the length of the preceding one will be indicated by the tape inasmuch as perforation E will not be made and perforation F will be the first perforation following the perforation B' which marks the beginning of an impulse. When the tape is passed through the transmitter, the impulse sent will be three times as long as that sent for a high light. In like manner, as the lights of the picture are less intense and the plate current through the tubes increases relays 23, 24 and 25 will remain open for the shadows of the picture and the impulses corresponding thereto will be indicated by the space intervening between initial impulse B' and the terminating perforations G, H and I. It will be seen therefore that each group of perforations represents a succeeding differential section of area of the picture to be transmitted and with the record tape so prepared may be used to control a transmitter in a manner so that an impulse of varying length or time duration will be transmitted in accordance with the intensity of light in the particular differential section of area. To economize in transmitting time, parts of the picture which are non-essential or contain no distinctive outlines may be either cut out of the picture or cut from the tape. For instance, in transmitting a picture of the head and shoulders of a man from a picture three inches square it may be convenient to eliminate the two upper corners about $\frac{3}{4}$ " wide by $1\frac{1}{2}$ " long as these contain no details of interest. If this is to be done the transmitting

station will telegraph this information to the receiving station for example by giving the location of the parts to be omitted and their dimensions preferably by specifying the number of impulses and number of rows of impulses corresponding to the omitted space or spaces.

Turning now to the operation of the receiving system, as shown in Fig. 2, we utilize any convenient receiver for receiving the impulses so sent out and a suitable recorder for preparing a perforated tape substantially identical with the transmitter tape. This recorder 9 may conveniently be a Creed perforator. The operation of receiver 8 and recorder 9 is well understood and it is not believed necessary to describe it in detail except so far as necessary to understand the method of reproduction of the picture. It will be seen that the operation of the elements thus far described produces a record tape at the transmitting end having indications thereon of the duration of impulses corresponding to the light intensity of a particular section of area of the picture to be transmitted and an identical record tape at the receiving end. This latter record tape may then be utilized in any suitable reproducer to reconstruct the picture.

A suitable reproducer adapted to utilize the tape record made at the receiving end is shown in Fig. 4 wherein we have indicated diagrammatically a Wheatstone standard automatic transmitter unit. As the operation of this transmitter unit is well understood by those skilled in the art it will not be particularly described except as it co-acts with the reproducer. Transmitter T is driven through a suitable motor not shown and is adapted to cause progressive movement of the tape 37 through its housing. The transmitter is adapted to open and close a circuit including magnet 46 and battery 47 for intervals in accordance with the perforations of the tape. Magnet 46 controls any suitable recording means herein shown by way of example as a light recorder. Tape 37 is also geared through the middle or guide perforations with drum 43 and driven through the driving motor of the Kleinschmidt perforator which is adapted to have secured thereon a suitable sheet of light sensitive film upon which the picture is to be recorded.

The light recorder may consist for example, of a light proof cabinet 44 for drum 43 having a slot 45 the edges of which serve as guides for a housing 38 movable longitudinally on the guides. The housing contains a light 39, and a lens 40, for projecting light through the slot into the casing containing the photographic film on which the picture is to be recorded. The magnet 46 controls the opening and closing of a shutter 41 interposed between the light and lens and thus controls the exposure of the film. The mag-

net will be arranged so that when the tape is perforated in such a manner as to correspond to a high light (short impulses and long spaces) of the picture, shutter 41 will be closed momentarily and then practically instantly opened so that the proportionate time of light exposure of the film is long. For a less intense high light the shutter will remain closed for a longer period causing less exposure and in a similar manner the length of the exposure of the film will decrease in accordance with the length of time the shutter is maintained closed whereby dots will be produced whose intensity corresponds to the length of the impulse transmitted. It may be stated that any suitable means is utilized to cause travel of the shutter with respect to the exposed portion of the drum 43 such, for instance, as rotational movement of drum 43 and translational movement of the light 39 and lens 40 by means of a screw thread driven through shaft which drives the drum and the perforated record.

It will be evident that the speed of drum 43 is entirely independent of that of the drum 3 of the transmitter because reproduction may be independent of reception and recording. The only condition which must be fulfilled is that a definite number of operations of a punching coil in a reproducer must take place for each complete rotation of the drum 3 and drum 43 must be chosen of such size or its speed so governed that the same number of perforation groups or impulses correspond to a complete revolution thereof. That is, the receiving end should provide for the same number of impulses per row as are transmitted by the transmitter per row. This, however, is taken care of in the design of the apparatus by providing the proper gear ratio between the elements causing relative movement between the shutter and drum 43 and those causing movement of tape 37.

While we have shown and described a photographic recorder for reproducing a picture it is evident that our invention is not limited thereto but that any other suitable recorder such as a chemical recorder may be used adapted to produce on the surface of drum 43 an impression the size or intensity of which is proportional to the length of the transmitted impulse.

By means of the arrangement described it will be noted that we utilize a process for transmitting pictures and the like which is essentially simple and reliable and which is free from the defects inherent in certain methods. It is also to be noted that we have avoided the necessity for simultaneous synchronous operation of the transmitting and receiving drums. Both the transmitter and the reproducer may be run independently at a speed as fast as their construction will permit. It is also evident that the reproducing of the picture may be stopped at any time.

without interfering with the operation of the transmitter in order to make any adjustments which may be desired or to utilize the circuit for more urgent business.

Having described our invention what we claim is:

1. A method of transmitting a picture which consists in illuminating the picture, conveying light from unit areas in succession to a light sensitive cell, converting the light intensity of successive areas into currents of different intensities, and producing a record therefrom in which each of the unit areas is represented by a section therein of the same duration, each section comprising an indication having a duration proportional to the light intensity from the corresponding unit area, and a complimentary interval and transmitting electrical impulses of length corresponding to the indication.
2. A method of transmitting pictures which consists in illuminating the picture, conveying light from unit areas thereof in succession to a photo-electric cell, converting variations in light intensity from successive areas into variations in current intensity therefrom, translating the current representing unit areas into a record in which each unit area is represented on the record by an indication having a duration proportional to its light intensity, transmitting electrical impulses of corresponding length, receiving the electrical impulses and indicating them on a surface in positions corresponding to the location of the unit areas corresponding thereto.
3. A method of transmitting pictures which consists in illuminating the picture, conveying light from unit areas thereof in succession to a photo-electric cell, converting variations in light intensity from successive areas into variations in current intensity therefrom, translating the current representing unit areas into a record in which each unit area is represented on the record by an indication having a duration proportional to its light intensity, transmitting electrical impulses of corresponding length, receiving the electrical impulses and indicating them on a surface in positions corresponding to the location of the unit areas corresponding thereto, with exposures having a time duration corresponding with the duration of the received impulses.
4. A method of transmitting pictures which consists in illuminating the picture, conveying light from unit areas thereof in succession to a photo-electric cell, converting variations in light intensity from successive areas into variations in current intensity therefrom, translating the current representing unit areas into a record in which each of the unit areas is represented on the record by a section of the same duration, each section comprising an indication having a duration

proportional to its light intensity and a complimentary interval, transmitting electrical impulses of length corresponding to the indication, receiving the electrical impulses and indicating them on a surface in positions corresponding to the location of the unit area corresponding thereto.

5. A method of transmitting pictures which consists in illuminating the picture, conveying light from unit areas thereof in succession to a photo-electric cell, converting variations in light intensity from successive areas into variations in current intensity therefrom, translating the current representing unit areas into a record in which each of the unit areas is represented on the record by a section of the same duration, each section comprising an indication having a duration proportional to its light intensity and a complimentary interval, transmitting electrical impulses of length corresponding to the indication, receiving the electrical impulses and indicating them on a surface in positions corresponding to the location of the unit area corresponding thereto, with exposures having a time duration corresponding with the duration of the received impulses.

6. A method of transmitting pictures which consists in illuminating the picture, conveying light from unit areas thereof in succession to a photo-electric cell, converting variations in light intensity from successive areas into variations in current intensity therefrom, translating the current representing unit areas into a record in which each unit area is represented on the record by an indication having a duration proportional to its light intensity, transmitting electrical impulses of corresponding length and of substantially equal intensity, receiving the electrical impulses and indicating them on a surface in positions corresponding to the location of the unit areas corresponding thereto.

7. A method of transmitting pictures which comprises, illuminating the picture, transmitting light from unit areas thereof in succession to a photo-electric cell, producing therefrom a corresponding fluctuating current output and thereby producing from the picture to be transmitted a perforated record tape, each perforation unit of said tape corresponding to a different section of area of said picture and the length of the perforation in each perforation unit being dependent upon the light intensity in the corresponding differential section of said picture.

8. A method of transmitting pictures which comprises illuminating the picture, transmitting light from unit areas thereof in succession to a photo-electric cell, producing therefrom a corresponding fluctuating current output and thereby producing from the picture to be transmitted a perforated record tape comprising a plurality of perfora-

- tion units, each perforation unit of said tape corresponding to a differential section of area of said picture, and each perforation unit having perforations marking the beginning and end of an impulse, the distance between said marking perforations defining the duration of an impulse and varying with the intensity of light in the differential section of said picture corresponding thereto.
9. The method of transmitting pictures which comprises illuminating the picture, conveying illumination from unit areas thereof to a photo-electric cell, producing therefrom a series of impulses corresponding to differences in illumination of the successive areas, transmitting a series of impulses corresponding to differential sections of area of the picture to be transmitted, controlling the duration of each of said impulses according to the intensity of light in the differential section corresponding thereto, receiving such impulses, recording the same by perforating a record strip or tape and reproducing the picture from said perforated strip.
10. In a transmitter for pictures and the like, the combination of means for perforating a record tape, means for controlling a transmitter from said perforated record tape, a series of relays each responsive to different strength currents for controlling said perforating means, and means sensitive to the intensity of light falling thereon for controlling said perforating means, whereby said perforating means will perforate said tape with marks of varying duration, said marks being proportional to the light intensity of the picture being transmitted.
11. In a transmitter for pictures and the like, the combination of means for perforating a record tape for controlling a transmitter, means comprising a plurality of relays for controlling said perforating means, and means sensitive to the intensity of light falling thereon for controlling said controlling means, whereby said controlling means is adapted to actuate said relays to perforate said tape in varying time durations which are directly proportional to the light intensity of the picture being transmitted.
12. In a transmitter for pictures and the like, the combination of means for perforating a record tape adapted to control a transmitter, means for controlling said perforating means comprising a plurality of relays, each having an actuating winding and an opposing winding, and means sensitive to the intensity of light falling thereon for controlling said controlling means.
13. In a transmitter for pictures or the like, the combination of means for perforating a record tape adapted to control a transmitter, means for controlling said perforating means comprising a plurality of relays, each comprising an actuating winding and an oppos-
- ing winding and said relays being so constructed and arranged as to be successively operated in accordance with predetermined increases in the current flowing therein, and means sensitive to the intensity of light falling thereon for controlling said controlling means.
14. In a transmitter for pictures or the like, the combination of means for perforating a record tape adapted to control a transmitter, said perforating means comprising means for making a perforation to indicate the beginning of an impulse and a plurality of means for making a perforation indicating the end of an impulse whereby the length of impulses may be controlled, means for controlling said perforating means, comprising a plurality of relays and means sensitive to the intensity of light falling thereon for controlling said controlling means.
15. In a transmitter for pictures and the like, the combination of means for perforating a record tape adapted to operate a transmitter, said means being constructed and arranged to strike a perforation marking the beginning of an impulse and having a plurality of punches adapted to strike perforations at varying distance therefrom to indicate the termination of an impulse, a plurality of means for controlling said plurality of punches comprising a plurality of relays, said relays being adapted to be operated successively in accordance with current therethrough and means sensitive to the intensity of light falling thereon for controlling said controlling means.
16. In a transmitter for pictures and the like, the combination of means for perforating a record tape adapted to control a transmitter, said perforating means comprising a punch adapted to make a perforation marking the beginning of an impulse and a plurality of punches, each adapted to make a perforation at a different distance from said initial perforation marking the termination of an impulse, a coil for controlling each of said punches, a relay for controlling each of said coils, said relays being constructed and arranged to operate successively upon predetermined increases of current and means sensitive to the intensity of light falling thereon for controlling said controlling means.
17. In a transmitter for pictures and the like, the combination of means for perforating a record tape adapted to control a transmitter, said means comprising a punch adapted to make a perforation marking the beginning of an impulse, a plurality of punches, each adapted to make a perforation marking an impulse of different length, a plurality of coils for preparing said last named punches, a plurality of relays for selectively energizing said coils in accordance with the value of current flowing through said relays, means sensitive to the intensity of light falling

thereon for controlling said controlling means and means comprising an interrupter for causing the periodic operation of said perforating means.

- 5 18. In a telegraph transmitter for pictures or the like the combination of means for perforating a record tape adapted to control a transmitter, means for controlling said perforating means comprising a plurality of re-
10 lays, each comprising an actuating winding and an opposing winding, and means to vary the amount of opposing torque developed and means sensitive to the intensity of light falling thereon for controlling said
15 controlling means.

In testimony whereof,

ERNST F. W. ALEXANDERSON.
